AT ROCKFORD, ILLINOIS, AS BARBER-COLMAN COMPANY.

YARN-CARRIER SUPPORT.

1,274,387.

Specification of Letters Patent.

Patented Aug. 6, 1918.

Application filed November 28, 1916. Serial No. 133,982.

To all whom it may concern:

Be it known that I, HOWARD D. COLMAN, a citizen of the United States, residing at Rockford, in the county of Winnebago and State of Illinois, have invented certain new and useful Improvements in Yarn-Carrier Supports, of which the following is a specification.

Spools, cheeses or other yarn masses, when taken from the spooler or winder on which they were produced, have heretofore been deposited in suitable receptacles for transportation to the warper creel, where the yarn masses were placed in position in the creel, one by one. When the spools or cheese cores were empty, they were removed, one by one, from the creel, and placed at points adjacent to the spooler or winder. These operations necessitated much rehandling of the yarn masses and empty spools or cheese cores. One of the objects of this invention is to reduce the amount of handling of the yarn masses and containers, and avoid the possibility of injury to the yarn which is incident to the previous methods of handling and transporting yarn masses. This object is attained by constructing the warper creel with removable sections adapted to be used at the spooler or winder as a receptacle or support for the yarn masses when removed from the spooler or winder, and adapted to be transported to and placed in the creel.

Another object of the invention is to provide a yarn-carrier support which shall permit rotation of the yarn carrier with a minimum amount of friction.

The invention also relates to the further improvements hereinafter described.

In the accompanying drawings Figure 1 is a fragmental vertical sectional view of a creel embodying the features of my invention, showing a trident in place in the supporting frame. Fig. 2 is a vertical sectional view taken approximately in the plane of dotted line 2 of Fig. 1. Fig. 3 is a fragmental longitudinal central sectional view of a spindle and rollers comprised in the trident. Fig. 4 is a sectional view of the trident.

While the invention may be used in connection with various forms of yarn masses, it is herein illustrated as embodied in ap-

paratus for supporting yarn masses in the form of cylindrical cheeses *a*. Each cheese 55 consists of yarn cross-wound upon a tubular core *b*. In the illustrative form herein shown, the axial opening of the cheese core is defined by inturned flanges *b*⁴.

In the creel the cheeses are rotatably supported upon spindles 1, four cheeses, in the present embodiment, being carried by each spindle. The cheese cores are not mounted directly upon the spindle, but are carried by rollers 2 which are rotatably supported upon the spindle. In the construction herein shown, each roller is formed of sheet metal. If desired, ball bearings may be interposed between the roller and the spindle. In the construction selected for 70 illustration, a sleeve 3 is mounted upon the spindle 1, the ends of said sleeve being expanded to form ball races 4. Each roller 2 comprises inturned end flanges 5 which are bent to form ball races 6. Between the 75 ball races 4 and 6 are placed balls 7. Inwardly of the ball races 6 the roller is provided with an annular flange or lip 8.

To lubricate the ball bearings a small quantity of oil *x* is placed in each roller 2 80 before the roller is placed upon the spindle, the oil being introduced through an opening 9 in the sleeve 3. The quantity of oil is such that the level of the oil never touches the sleeve 3 whether the spindle is in horizontal or in vertical position, the oil level being such that when the spindle is tilted at any angle, the oil never reaches the lip 8. By reason of the well-known tendency of oil to creep over a surface, sufficient oil 90 reaches the ball bearings to keep the latter properly lubricated. When the cheeses are rotated, the oil *x* is spread over the inner periphery of the rollers 2, and when the cheeses are stopped some of the oil creeps 95 over the flanges 5 and the lips 8 and thus enters the bearings. The lip 8 increases the distance the oil must creep and thus reduces to the desired extent the amount of oil that reaches the bearings. The amount 100 of oil that reaches the bearings at any given stoppage is so small that the supply contained in the roller lasts for a long time.

The opposite ends of each roller are slightly reduced in diameter to provide surfaces 10 for supporting the bearing flanges

b^4 of the cheese cores, these surfaces being connected to the remainder of the periphery of the roller by means of annular tapering shoulders 11. By reason of such reduction 5 in diameter the roller has a generally crowning form which prevents the cheese from moving laterally into contact with the adjacent cheeses when revolving in the creel, and restores the cheese to central position if 10 placed. When one of the flanges b^4 is on the highest portion of the periphery of the roller, that side of the cheese moves a little faster than the other side, and hence the cheese is caused to cant, as a result of which 15 the cheese moves sidewise as it revolves until both flanges b^4 are again on the surfaces 10.

As shown in Fig. 3, the surfaces 10 on the adjacent ends of the rollers extend so close to each other that there are no gaps between 20 the rollers into which the flanges b^4 can drop.

The greatest diameter of the roller 2 is sufficiently less than the smallest internal diameter of the cheese core so that the latter 25 may be readily slipped on and off the roller by the operative.

In the construction herein illustrated, the spindles 1 are arranged in groups of three, each group being fixed to an elongated base 30 12. The spindles 1 are secured to the base 12 by means of attaching members 13. Upon the outer end of each spindle is a tubular tip or cap 14 which, for convenience in manufacture, is rotatably mounted upon 35 a sleeve 15, said sleeve having an outturned flange upon its inner end. The sleeves 3 are spaced away from each other and from the attaching member 13 and the tip 14 by means of sleeves 16 having out-turned end 40 flanges which abut the flanges of the sleeves 3 and 15. The series of sleeves 3, 15 and 16 is clamped against the attaching member 13 by means of a nut 17 screwed upon the outer end of the spindle 1.

45 A spool 18 is rotatably mounted upon each sleeve 16. As shown in Fig. 3, the ends of the rollers 2 are countersunk so as to overhang the spools 18. These spools receive any yarn which may get between the rollers 2 or 50 between said rollers and the attaching member 13 and the tip 14. In case some yarn should become wound upon one of the spools 18, the yarn may be readily unwound therefrom by the operative, since the spool will 55 rotate freely as the yarn is withdrawn.

Each base 12 with its row of spindles 1 will hereinafter be termed a trident.

The tridents are adapted to be used at the 60 winder as a receptacle or a support for the cheeses when the latter are removed from the winder. When in use at the winder, the tridents rest upon the bases 12 with the spindles 1 in upright position. When in such position the cheese cores b on a given 65 spindle rest upon one another, as shown in

Fig. 4. When the tridents are in use in the creel, the spindles occupy a horizontal position. When the warp-beam is revolved, the cheeses move laterally until each is properly located on its roller as shown in Figs. 1 and 70 3. As indicated in Fig. 4, when the trident is placed in the creel frame, the cheese nearest the tip of the spindle is so positioned that its bearing flanges b^4 are both on the high 75 portions of two adjacent rollers, and hence 80 said cheese does not tend to move laterally, but the cheeses nearer the base 12 push said cheese laterally until its bearing flanges are at different elevations, whereupon said cheese centers itself upon its roller. All of the 85 cheese cores are then out of contact with each other, as represented in Fig. 1. It will be seen that the cheeses need not be manually placed in running position upon their 90 respective rollers.

The framework of the creel may be of any suitable character. For example, the framework may be composed of a plurality of bays each including a compartment adapted to support a plurality of tridents arranged one above the other as fully disclosed in Patent No. 1,207,138, granted December 5, 1916. Herein only a portion of the creel frame is illustrated. At the left-hand side of the bay is a socket 19 to receive one 95 end of the base 12 of a trident. At the right-hand side of the bay are sockets 20 (Figs. 1 and 2) to receive the tips 14. Each bay is provided at one side with a gate 21 hinged at 22. The gate is held shut by means of a 100 projection 23 on the gate adapted to lie in a recess 24 on a locking member 25 fixed to the creel-frame. Each gate is provided with guide rods 26 for guiding the threads from the cheeses to the warper.

The mounting of a plurality of cheeses upon each spindle conduces to a very compact arrangement of the cheeses in the creel.

The winder operatives place the cheeses upon the tridents in such a manner that 110 when the tridents are set in the creel-frame the yarn shall unwind from the upper portions of the cheeses. As the trident may be set in the creel-frame with either end up, the warper tender can place the tridents 115 without giving any attention to the matter of seeing that the yarn unwinds from the upper part of the cheeses.

It will be apparent that the creel, comprising as it does tridents each of which is 120 supplied with twelve cheeses at the winder, may be filled and emptied very quickly, and with a minimum of handling of the cheeses.

Suitable means may be employed to arrest the rotation of the cheeses when the warper 125 stops. Herein I have indicated in Fig. 2 brake devices 27 located at the rear side of the creel-frame and arranged to engage the peripheries of the yarn masses upon the cores b , said devices being similar to those 130

fully described in my copending application Serial No. 27,093, (Patent No. 1,207,138).

It will be evident that the construction herein disclosed simplifies the handling of 5 the cheeses and permits the cheeses to be rotated in the warping process with a minimum amount of friction.

This application is a continuation in part of application Serial No. 781,919, filed July 10 30, 1913, and application Serial No. 27,093, filed May 10, 1915, (Patent No. 1,207,138).

I claim as my invention:

1. A device adapted to receive tubular yarn containers at a winder, and also adapted to support said containers while the latter are being unwound by a warper, comprising a base arranged to rest interchangeably upon its lower side and upon one of its edges, a spindle attached to said base, and 15 a plurality of rollers rotatably mounted on said spindle, each of said rollers being of smaller diameter than the interior diameter of the yarn containers, whereby the yarn containers are freely placeable upon and removable from the spindle when the latter is in upright position, each of said rollers being constructed to hold its yarn container out of contact with adjacent yarn containers when the spindle is in horizontal position. 20

2. A device adapted to receive tubular yarn containers at a winder, and also adapted to support said containers while the yarn is being unwound by a warper, comprising a member, a spindle attached to said member, and a plurality of rollers rotatably mounted on said spindle, each of said rollers being of smaller diameter than the interior diameter of the yarn containers, whereby the yarn containers are freely placeable 25 upon and removable from the spindle when the latter is in upright position, each of said rollers being constructed to hold its yarn container out of contact with adjacent yarn containers when the spindle is in horizontal position. 30

3. A creel having, in combination, a frame having a compartment therein, a creel section consisting of a base and a plurality of yarn-mass-supporting spindles, each secured at 35 one end to said base, means at one side of the compartment for supporting said base, means at the other side of the compartment for supporting the outer ends of the spindles, and a gate movably connected to the 40 frame for closing the compartment, said gate having a plurality of guides for the threads of yarn masses mounted on said spindles. 45

4. A creel having, in combination, a frame having a compartment therein, a creel section having an elongated base and a row of spindles, said row extending longitudinally of the base, each spindle being long enough to support a plurality of yarn masses, means 50 at one side of said compartment for support-

ing one end of said base, means at the other side of said compartment for supporting the outer ends of the spindles in horizontal position, and a movably mounted frame for closing the compartment, said last mentioned frame having a plurality of guides for the threads of the yarn masses mounted on said spindles. 70

5. A creel having, in combination, a creel section consisting of a base; a plurality of spindles each secured at one end to said base; a plurality of rollers rotatably mounted on each of said spindles; and a creel frame having means for supporting one edge of said base and means for supporting the outer ends of said spindles, said base being adapted to support said spindles in upright position when the creel section is removed from the frame. 75

6. In combination, a base, a spindle on said base of sufficient length to support a plurality of tubular yarn containers, and means on the spindle, arranged to act on the interiors of the containers, to keep the containers out of contact with each other 80 when running. 85

7. A creel section comprising a base having a spindle fixed thereon; and a plurality of rollers rotatably mounted on said spindle, each of said rollers being adapted to support a tube having yarn wound thereon. 90

8. A device adapted to receive tubular yarn containers at a winder, and also adapted to support said yarn containers while the yarn is being unwound by a warper, comprising a member, a spindle attached to said member; and a plurality of rollers rotatably mounted on said spindle, each of said rollers being adapted to support a yarn container 100 independently of the other rollers. 105

9. A creel having, in combination, a frame having a compartment therein, a creel section having an elongated base and a row of spindles, said row extending longitudinally of the base, each spindle being long enough 110 to support a plurality of yarn masses, means at one side of said compartment for supporting one end of said base, means at the other side of the compartment for supporting the outer ends of the spindles in horizontal position, and a gate pivoted to the frame upon a vertical axis for closing the compartment, said gate having a plurality of guides for the threads of the yarn masses 115 mounted on said spindles. 120

10. A support for a tubular yarn container comprising a roller adapted to lie within the container, the opposite ends of said roller being reduced in diameter to form annular supporting surfaces for said carrier, said 125 surfaces being connected to the remainder of the periphery of the roller by means of annular tapering shoulders, and means for supporting said roller for rotation.

11. A support for a tubular yarn con- 130

tainer comprising a member adapted to lie within the container, the opposite ends of said member being reduced in diameter to form supports for the ends of the container, said member being of generally crowning form, and means for supporting said member for rotation on a horizontal axis.

12. A creel having, in combination, a frame, and a creel section consisting of a base and a plurality of yarn-mass-supporting spindles each secured at one end to said base, the creel frame having means to support said base and means to support the outer ends of said spindles, the base-supporting means and the spindle-supporting means being such as to permit the creel-section to be lifted out of place.

13. A creel having, in combination, a base, a spindle secured at one end to the base, means for removably supporting the base, and means for removably supporting the opposite end of the spindle, said base being adapted to support the spindle in upright position when the base and the spindle are removed from said supporting means.

14. A creel having, in combination, a creel section consisting of an elongated base and a plurality of spindles, a support having a socket to removably receive one edge of said base, and means to support the tips of the spindles.

15. A warper creel having, in combination, a frame having a compartment therein, a base removably mounted in said compartment, a plurality of spindles on the base, a plurality of rollers on each spindle, each roller being arranged to support a single yarn carrier, and a set of thread guides for the threads of said yarn carriers, said set being movable into and out of operative relation to the compartment.

16. A warper creel having, in combination, a frame having a compartment therein, a plurality of yarn-carrier supports removably positioned in the compartment, a gate for closing the compartment, and thread guides on the gate for the threads of said yarn carriers.

17. A warper creel having, in combination, a frame, a vertical row of horizontally positioned spindles in the frame, a plurality of rollers on each spindle, each roller being arranged to support a single yarn carrier, a gate arranged to swing into position alongside the row of spindles, and thread guides on the gate for the threads of the yarn carriers.

18. A warper creel having, in combination, a frame having a compartment therein, a removable creel section consisting of a base and a plurality of yarn-mass supporting spindles, each rigidly secured at one end to said base, means at one side of the compartment for removably supporting said

base, means at the other side of the compartment for removably supporting the outer ends of the spindles, and a gate pivoted to the frame for closing the compartment.

19. A creel having, in combination, a frame, braking means at one side of the frame, movable thread-guiding means at the other side of the frame, and creel sections removably mounted in the frame between the braking means and the thread-guiding means.

20. A creel having, in combination, a frame having a compartment therein, yarn-carrier supports in said compartment, a series of brakes at one side of the compartment, there being a brake for each yarn carrier, and a set of thread guides for the threads of said yarn carriers, said set being movable into and out of position to close the other side of the compartment.

21. A warper creel having, in combination, a frame, a vertical row of horizontal spindles in the frame, each spindle being long enough to support a plurality of yarn masses, means on each spindle to keep the yarn masses on such spindles out of contact with each other when rotating to permit adjacent yarn masses to revolve at different speeds, and a gate pivoted to the frame upon a vertical axis, said gate having a plurality of guides for the threads of all of the yarn masses mounted on said spindles.

22. A creel having, in combination, a frame having a compartment therein, devices in said compartment for supporting a plurality of yarn carriers, the rear side of said compartment being closed to the insertion of yarn carrier supporting devices, and a gate pivoted to the frame for closing the forward side of said compartment, said gate having means to guide the threads of yarn masses supported by said devices.

23. A creel having a spindle and a roller rotatably mounted upon the spindle, said roller being intended to support a tubular yarn container having internal bearings at its ends and a sleeve of larger internal diameter extending from one bearing to the other, the ends of the roller being reduced in diameter to form supports for said end bearings, the portion of the roller intermediate said reduced ends being out of contact with said sleeve.

24. A yarn-carrier support having, in combination, a spindle, a plurality of yarn-carrier-supporting rollers mounted upon the spindle, and a yarn-receiving spool rotatably mounted on the spindle between the rollers.

25. A yarn carrier support having, in combination, a spindle, a plurality of rollers mounted upon the spindle, and a spool rotatably mounted on the spindle between the rollers, the ends of the rollers overhanging said spool.

26. A creel section comprising a base hav-

ing a spindle thereon; and a plurality of rollers on said spindle, each roller having a crowned periphery, each roller being adapted to support a yarn carrier, the spaces between the rollers being insufficient for the entrance of yarn carriers.

27. A warper creel having, in combination, a frame having a compartment therein, a base removably mounted in said compartment, a spindle on the base, a plurality of rollers on the spindle, each roller being arranged to support a single yarn carrier, a gate for closing the compartment, and thread guides on the gate for the threads of said 15 yarn carriers.

28. A warper creel having, in combination, a frame, a plurality of parallel horizontal spindles in the frame, and a plurality of rollers upon each spindle, each roller being arranged to support a single yarn 20 carrier.

29. A warper creel having, in combination, a frame, a base removably mounted in the frame, a spindle on the base, and a plurality of rollers on the spindle, each roller 25 being arranged to support a single yarn carrier.

In testimony whereof, I have hereunto set my hand.

HOWARD D. COLMAN.
